UNITED STATES PATENT OFFICE.

SAMUEL N. SILVER, OF AUBURN, MAINE.

MOTOR.

SPECIFICATION forming part of Letters Patent No. 254,712, dated March 7, 1882.

Application filed January 21, 1882. (Model.)

To all whom it may concern:

Be it known that I, SAMUEL N. SILVER, of Auburn, in the county of Androscoggin and State of Maine, have invented a new and Improved Motor, of which the following is a full, clear, and exact description.

The object of my invention is to provide a new and improved motor or device for applying power in a very effectual and economical manner.

The invention consists of one or more sliding and reciprocating cylinders, containing pistons held in these cylinders by latches, which pistons are each adapted to slide on a central rod surrounded by a coil-spring, to which pistons rocking arms are pivoted, which are loosely mounted on a shaft, these arms being provided with pawls or other suitable clutching devices for rotating the shaft. When the cylinders are pressed downward the springs are brought in tension, and when the springs exert the power stored in them they rotate the shaft, as will be fully described hereinafter.

Reference is to be had to the accompanying drawings, forming part of this specification, in which similar letters of reference indicate corresponding parts in all the figures.

Figure 1 is a front longitudinal sectional elevation of my improved motor on the line $x-x$, Fig. 3. Fig. 2 is a side longitudinal elevation of the same. Fig. 3 is a sectional plan view of the same on the line $y-y$, Fig. 1.

The shaft A is journaled in a suitable frame, B, and has a fly-wheel, C, and a pulley, D, rigidly mounted on the ends; or in place of the fly-wheel and pulley any other wheels or cranks can be mounted on this shaft. The shaft A is also journaled in the shanks E of a frame, which shanks each have a rectangular bend, E', at that part at which the shaft is journaled, and from this bend the shanks extend downward as rods E². At each side of each shank E an arm, F, is loosely mounted on the shaft, and to one end of each arm is pivoted a spring-pawl, G, engaging with a ratchet-wheel, G', rigidly mounted on the shaft A; or in place of the pawl G a spring friction-clutch pawl, H, adapted to catch on the edge of a friction-wheel, H', mounted on the shaft A, may be pivoted to the end of each arm F; or, as shown, of each pair of arms F one may be provided with

a pawl, G, and the other with a friction-clutch pawl, H, and the corresponding ratchet and friction wheels, G' and H', must be mounted on the shaft A, adjoining the arms F F, as shown. 55 Those ends of the arm F opposite the ones to which the pawls are pivoted are each provided in the end with a longitudinal recess or slot, a, through which a screw or pintle, J, passes into a cylindrical piston, K, provided with a longitudinal slot, K', extending from the top almost to the bottom, which piston is loosely mounted on one of the rods E², projecting downward from the bends E' of the shanks E. These cylindrical pistons must be provided with the 60 slots K', so that the bends E' do not interfere with the reciprocating movement of these pistons. The pistons are contained in cylinders L, provided with longitudinal slots L' in opposite sides, through which slots the screws or pintles 70 J pass. The cylinders L are provided with pivoted hook-latches M, which are pressed by springs N, attached to the cylinders L, through slots N' in these cylinders into notches O in the pistons K, whereby when the cylinders L 75 are moved downward the pistons K will move downward with them. The cylinders L are drawn upward or toward the shaft A by springs P, attached to the bends E', and to the lower ends of the cylinders L. The pistons K 80 are forced in the same direction as the cylinders L by springs Q, coiled around the rods E², and resting against the lower end of the pistons K, and against cylindrical sockets R, screwed on the lower ends of the rods E² and fitting 85 within the lower ends of the cylinders L. The lower ends of the cylinders L are surrounded by cylindrical guide-frames S, also attached to the lower ends of the rods E², between which sockets R and cylindrical frames S the lower 90 ends of the cylinders L are guided. The cylinders L are provided with longitudinal slots K² for the passage of the bends E'.

The operation is as follows: If a downward pressure is exerted on the cylinders L, they will 95 move downward, and their latches M M will draw the pistons K downward with these cylinders, and these pistons draw downward the outer ends of the arms F, thereby raising the inner ends of the same, and causing the pawls G or H to slide over the edges of their corresponding wheels, G' or H'. By this downward

movement of the cylinders L the springs P are stretched and the springs Q are compressed. As soon as the pressure is removed from the cylinders L the springs P and Q will force the cylinders L and the pistons K upward, causing the pawls G or H to catch on the wheels G' or H', and to rotate the shaft A in the direction of the arrow a'. Then the cylinders are again depressed and released, to be drawn upward 10 by the springs, and so on. Both cylinders L can be depressed together; or they can be operated alternately, so as to obtain a continuous rotation of the shaft. The cylinders can be operated by hand or foot power, by animals, 15 water-power, or steam, gas, or air engines. The power is stored and accumulated in the springs, and they furnish the power as it is required. A very great amount of power is economized, as I will now show. For instance, 20 if my motor is operated by a steam-engine, and if at any time there is very little resistance offered to the shaft, I simply decrease the number of strokes of the engine, thereby increasing the time required to depress the cylinders, but not affecting the rapidity of the 25 rotation of the shaft, but decreasing its power. I gain very much in power by this manner of operating, for by reducing the number of strokes of the engine the friction is avoided to a very 30 great extent, and consequently the power required to overcome the friction is economized.

Having thus fully described my invention, I claim as new and desire to secure by Letters Patent—

35. 1. A motor made substantially as herein shown and described, and consisting of reciprocating devices for bringing springs in tension, combined with devices for rotating a shaft by these stretched springs, as set forth.

40. 2. In a motor, the combination, with a shaft, of the rocking arms mounted loosely on the shaft, and provided with devices for acting on the shaft, and of the reciprocating cylinders

provided with springs for forcing the cylinders upward, substantially as herein shown and 45 described, and for the purpose set forth.

3. In a motor, the combination, with the shaft A, of the rocking arms F, provided with devices for acting on the shaft, the reciprocating cylinders L, containing pistons K, connected 50 with the ends of the arms J, and of the springs P, substantially as herein shown and described, and for the purpose set forth.

4. In a motor, the combination, with the shaft A, of the rocking arms F, provided with devices for acting on the shaft, the reciprocating cylinders L, containing the pistons K, each provided with a longitudinal slot K' and sliding on the rods E², and of the springs Q, substantially as herein shown and described, and 60 for the purpose set forth.

5. In a motor, the combination, with the shaft A, of the rocking arms F, provided with devices for acting on the shaft A, the cylinders L, the pistons K, the rods E², the springs Q, 65 and the latches M, substantially as herein shown and described, and for the purpose set forth.

6. In a motor, the combination, with the shaft A, of the rocking arms F, provided with devices 70 for acting on the shaft A, the cylinders L, the pistons K, the rods E², the springs Q, the clutches M, and the springs N, substantially as herein shown and described, and for the purpose set forth.

7. In a motor, the combination, with the shaft A, of the rocking arms F, provided with devices for acting on the shaft A, the cylinders L, the pistons K, the rods E², the springs Q, the cylindrical sockets R, and the guide-frames 80 S, substantially as herein shown and described, and for the purpose set forth.
